ECLIPSE MACHINE COMPANY, OF ELMIRA HEIGHTS, NEW YORK, A CORPORATION OF
NEW YORK

ENGINE STARTING APPARATUS

Application filed January 30, 1929. Serial No. 336,313.

This invention relates to engine starting apparatus, and more particularly to means of the inertia type for starting internal combustion engines.

5 It has heretofore been proposed to employ a small high speed flywheel as a reservoir for the storage of energy, and to utilize energy stored therein for starting an internal combustion engine. Devices of this character 10 have, in certain instances, embodied manually operable means for rotating the flywheel at high speed, and have also embodied power means, such as an electric motor, for actuating the flywheel.

15 It is an object of this invention to provide starting mechanism of the above type, including novel means for drivably connecting the electric motor with the flywheel, whereby the latter may be rotated.

20 Another object is to provide novel automatic means for drivably connecting the source of power, such as an electric motor, with a rotatably mounted driven member.

25 A further object is to provide novel centrifugally operated means for drivably connecting an electric motor with a rotatably mounted driven member.

30 A still further object is to provide a centrifugally operated clutch for automatically establishing a driving relation between an electric motor and a flywheel, which latter preferably constitutes a part of a self-contained engine starting device.

35 Two embodiments of the present invention are shown in the accompanying drawing, but it is to be expressly understood that the drawing is for purpose of illustration only and is not designed as a definition of the limits of the invention, reference being had for this 40 purpose to the appended claims.

Referring to the drawing, wherein like reference characters refer to like parts throughout the several views,

45 Fig. 1 is a longitudinal view, partly in section, illustrating one embodiment of the present invention;

Fig. 2 is a partial sectional view on an enlarged scale illustrating the connecting means shown in Fig. 1; and

50 Fig. 3 is a detail sectional view with parts

broken away, of another embodiment of the invention.

Referring more particularly to Figs. 1 and 2, the starting mechanism therein shown comprises a housing 6 adapted to be secured, as by means of bolts 7, to the engine crank case, a portion of which is shown at 8. Within the housing 6 is rotatably mounted a small high speed inertia member or flywheel 9, which is adapted to drive, through suitable reduction gearing and yielding means such as a clutch, a jaw member 10. Any suitable type of reduction gearing may be employed in combination with suitable clutch means, and since these elements per se constitute no part of the present invention the same are not illustrated. The jaw 10 is adapted to be moved into driving engagement with a jaw 11 rigidly attached to the engine crank shaft, or an extension thereof.

Means are provided for rotating the flywheel 9 at high speed in order to store sufficient energy therein for cranking the engine. In the form shown, said means include an electric motor 12 which may be removably secured to the housing 6 as by means of screws 13. The inner end of the armature shaft 14 of the electric motor is rotatably mounted as by means of a ball bearing 15 in the end wall 16 of housing 6.

80 Drivably connected, in any suitable manner, to the end of armature shaft 14 is a disk 17 which is rigidly held in driving engagement with said shaft, as by means of a screw 18 and locking member 19. Disk 17 embodies a hub portion 20 and a peripheral portion 21 which lies in a different vertical plane from the flat central portion 20a of the disk, the central portion and the peripheral portion 21 being connected by a cylindrical portion 22, the sides of which extend substantially parallel to the longitudinal axis of armature shaft 14. The outer surface of cylindrical portion 22 is threaded as at 23 to receive a nut or annular disk 24. The peripheral portion 21 and the member 24 form an annular pocket within which are slidably mounted a plurality of segmental shoes 25 constituting centrifugally actuated clutch members which are adapted for radial movement relative to

disk 17 but are held against rotary movement with respect to said disk, said weights being mounted in radial pockets or grooves formed in the disk for this purpose. The walls of 5 the pockets are indicated at 25a.

The nut 24 is provided with a plurality of pins 26 which project inwardly into the space or pocket between said nut and the peripheral portion of disk 17. These pins constitute 10 spacing and supporting members for a plurality of coil springs 27, one end of each of said springs having engagement with member 24 and the opposite end extending into a recess formed in the adjacent face of the 15 segmental wedge 25.

The portion 21 of disk 17 is provided adjacent its periphery with an inclined surface 28 which engages correspondingly inclined portions provided adjacent the inner faces of 20 the peripheries of the weights 25.

When the circuit to the electric motor 12 is closed, shaft 14 rotates at high speed, carrying therewith disk 17, member 24 and the centrifugally actuated members 25. As the 25 speed of rotation increases the centrifugal force acts to move segmental weights or clutch members 25 radially into engagement with the adjacent surface of flywheel 9. The inclined surface 28 prevents direct radial 30 movement of members 25 and said weights have a combined longitudinal movement and radial movement relative to the armature shaft 14. Springs 27 resist this compound movement. The centrifugal force reaches 35 such a value, however, that members 25 move into engagement with the overhanging portion 9a of the rim of the flywheel to establish a driving connection between the motor and flywheel, whereby the latter is rotated at high 40 speed.

When the flywheel has been brought to the desired speed of rotation, i. e., when sufficient energy has been stored in the inertia member to crank the engine, the circuit to 45 the electric motor may be opened, whereupon springs 27 are effective to return the segments 25 to normal or "collapsed" position. Flywheel 9 now rotates freely and drives the jaw member 12. The latter is then moved in any 50 suitable manner, as is well understood in the art, into engagement with jaw member 11, whereby the energy of the flywheel is rendered effective to crank the engine. When 55 the engine operates under its own power the engine crank shaft rotates faster than member 10, and the inclination of the teeth of jaw members 10 and 11 act to move the jaw 10 out of driving engagement, whereupon the parts 60 are returned to normal position.

In Fig. 3 there is illustrated another embodiment of the invention which is quite similar in structure to that disclosed in Figs. 1 and 2. The segmental weights 36 in this embodiment, however, are not provided with recesses to receive coil springs, since a single

dish-shaped spring 37, which surrounds the threaded member 38 and bears at its large periphery against the faces of the segments 36 and at its small periphery against member 38, is provided to normally maintain the members 36 in non-driving position. When the latter are moved radially by centrifugal force into engagement with the adjacent surface 39 of the overhanging rim of the flywheel 40, the inclined faces of the centrifugal members and the inclined face provided on disk 17 are still in engagement. Accordingly, when the motor is deenergized, spring 37 is effective, due to the said inclined surfaces, to return the centrifugal members 36 to normal position out of driving engagement. 70 75 80 85 90 95 100 105 110 115 120 125 130

What is claimed is:—

1. In engine starting apparatus of the type embodying an engine engaging member and means including a flywheel for driving the same, means for rotating said flywheel comprising a high speed shaft, a disk drivably connected thereto, centrifugally actuated members having engagement with said disk and adapted to move radially into driving engagement with the flywheel, and yielding means for normally maintaining said centrifugally actuated members in non-driving position. 95

2. In a self-contained engine starter of the type adapted to be removed as a unit from said engine and embodying a high speed flywheel, power means for rotating said flywheel, and means for automatically establishing a driving connection between said power means and flywheel including a plurality of centrifugally actuated members operatively connected with the power means and adapted to directly engage the flywheel, yielding means for normally maintaining said centrifugally actuated members in retracted position, and means operatively connected to the power means and the centrifugally actuated members for imparting lateral movement to 110 said centrifugal members. 100 105 110 115 120 125 130

3. In starting apparatus of the type embodying a member adapted for longitudinal movement into driving engagement with a member of the engine to be started, means including a flywheel having an overhanging rim for actuating said engine engaging member, and means for rotating said flywheel to store energy therein, said last named means including a plurality of centrifugally actuated members, and yielding means and a member having inclined surfaces for normally maintaining said centrifugally actuated members in non-driving position, said centrifugally actuated members having a combined radial and a longitudinal movement with respect to 115 120 125 130 said flywheel.

4. In a self-contained starting apparatus adapted to be connected as a unit to an engine to be started and embodying a jaw

member which is longitudinally movable into engagement with a member of the engine to be started, means including a flywheel for rotating said engine engaging member, said 5 flywheel having an overhanging rim, an electric motor disposed substantially coaxially with said flywheel, an armature shaft for the motor extending into the plane of the overhanging rim of said flywheel, a disk carried 10 by said shaft, centrifugal members slidably carried by said disk, said disk having an inclined surface engaging correspondingly inclined surfaces on said centrifugal members whereby the latter have a combined radial 15 and a longitudinal movement, and yielding means for resisting movement of said centrifugal members.

5. In apparatus of the class described, a driving member, a driven member, a disk 20 mounted on said driving member and having an inclined surface, a plurality of centrifugally actuated members slidably carried by said disk, means disposed substantially parallel to the axis of rotation of the driving member for resisting radial movement of 25 said centrifugally actuated members, and means carried by said disk and having engagement with said members for preventing relative rotation between said disk and members, the latter being adapted to move radially into driving engagement with the driven member.

6. In apparatus of the type embodying a member adapted for longitudinal movement 25 into driving engagement with a member of the engine to be started, means for driving said engine engaging member including a flywheel having an overhanging rim, a motor disposed substantially coaxially with said flywheel and having the armature shaft thereof 30 extending into the plane of the overhanging flywheel, a disk carried by said motor shaft and rotatable therewith, radially movable centrifugally actuated members slidably carried by said disk, and yielding means for resisting radial movement of said centrifugally 45 actuated members.

7. In combination with a rotatable member to be driven, driving means therefor including centrifugally actuated members, yielding means for normally maintaining said centrifugally actuated members in non-driving position, and means for imparting a combined radial and longitudinal movement 55 to said centrifugally actuated members to move the same into driving engagement with the member to be driven.

8. In a self-contained starting device for 59 internal combustion engines adapted to be secured as a unit to an engine to be started, an engine engaging member, means including a high speed flywheel for actuating said engine engaging member, and means for rotating said flywheel at high speed to store energy 65 therein, said last named means including a

motor, centrifugally actuated members drivably connected to said motor and adapted to move radially into driving engagement with the flywheel, and means for yieldingly resisting radial movement of said centrifugally 70 actuated members.

9. In apparatus of the class described, clutch mechanism including a driving member, a member to be driven, a disk carried by the driving member and having a plurality of radially extending walls forming pockets a plurality of segmental clutch members slidably in said pockets, and yielding means for resisting movement of said clutch members, the latter being adapted for driving engagement 80 with the driven member.

10. In a starting device for engines, an engine engaging member, means including a high speed flywheel for actuating said engine 85 engaging member, means for rotating said flywheel at high speed to store energy therein, centrifugally actuated members operatively connected to said rotating means and adapted to move radially into driving engagement 90 with the flywheel, and means for retracting said centrifugally actuated members to disengaged position.

11. An engine starter including a driving member adapted to crank a member of the engine to be started, an inertia device operatively connected therewith, an electric motor coaxially aligned with the inertia device, and centrifugal means for automatically connecting the motor to the inertia device following 100 energization of the motor.

12. An engine starter including a driving member adapted to crank a member of the engine to be started, an inertia device operatively connected therewith, an electric motor normally disengaged from the inertia device, 105 centrifugal means for automatically connecting the motor with the inertia device following energization of the motor, and means for withdrawing said centrifugal means 110 from driving position upon de-energization of the motor.

In testimony whereof I have signed this specification.

ROLAND CHILTON.
